UNITED STATES PATENT OFFICE.

JOHN F. FUTCHER, OF CHICAGO, ILLINOIS, ASSIGNOR OF ONE-HALF TO J. FORD HAWES, OF CHICAGO, ILLINOIS.

HUMIDIFYING DEVICE.

Application filed February 8, 1922. Serial No. 535,109.

To all whom it may concern:

Be it known that I, JOHN F. FUTCHER, a citizen of the United States, residing at Chicago, in the county of Cook and State 5 of Illinois, have invented certain new and useful Improvements in Humidifying Devices, of which the following is a specification.

My invention belongs to that general 10 class of devices known as humidifiers, and relates particularly to an apparatus for supplying water vapor to an internal combustion engine or the like. It also relates to a device for removing vapors from the 15 crank case of the engine, washing and purifying the same and returning them to the engine to be used for power purposes.

The invention has among its objects the 20 production of a device of the kind described that is simple, compact, durable, reliable, efficient and satisfactory for use wherever found applicable. It has particularly as an object the production of a device of the kind described which will uniformly supply 25 moisture to the ingoing charge of the engine under all weather conditions, and which will make the engine more efficient, securing increased power, flexibility and pick-up, and avoid the forming and accumulation 30 of carbon in the engine cylinder. It also has as an object the production of a device of the kind described which will remove vapors from the crank case of the engine, thereby purifying the lubricating oil and 35 utilizing the products drawn off, which would otherwise be wasted, for further power purposes.

Many other objects and advantages of 40 the construction herein shown and described will be obvious to those skilled in the art from the disclosures herein given.

To this end my invention consists in the 45 novel construction, arrangement and combination of parts herein shown and described, and more particularly pointed out in the claims.

In the drawings, wherein like reference 50 characters indicate like or corresponding parts,

Fig. 1 is a sectional view through my improved apparatus, a portion of the parts omitted;

Fig. 2 is a sectional view taken substantially on the line 2—2 of Fig. 1;

Fig. 3 is a sectional view taken substantially on the line 3—3 of Fig. 1;

Fig. 4 is a sectional view taken substantially on the line 4—4 of Fig. 1;

Fig. 5 is a view in elevation, portions being shown in section, illustrating the installation of the device; and

Fig. 6 is a top plan view of the receptacle forming a part of the apparatus.

Referring to the drawings, in which the preferred embodiment of the invention is shown, there is provided a container or receptacle of the desired size, shape and material, and constructed of the preferred number of parts. As illustrated, this consists of a casing part 1, provided with a bottom 2 and closure 3, the closure being preferably constructed so that it may be removed, as found desirable. The closure when made removable may be secured in place in any suitable manner. As shown it is removable, but when secured in place it is with a tight leakproof joint and with the part 1 and bottom 2 forms substantially a unitary structure, it being understood that any equivalent construction may be adopted other than that shown.

Referring particularly to Fig. 1, part 1 is provided with a threaded flange 4, arranged to cooperate with the internally-threaded ring or coupling 5; constructed to engage with the flange 6 on part 3, this providing a union. Packing material or gasket 7 may be arranged between the parts if desired. With this construction, by loosening the ring 5, the closure 3 may be conveniently lifted off and removed, permitting access to the interior of the device for inspection, cleaning, or replacement of the parts.

Within the casing I prefer to arrange one or more partitions 8 and 9, which may be of the desired size and shape, and of suitable material for the purpose. As shown, these are constructed in the form of plates provided with openings or apertures 13 therethrough. These plates may be supported and maintained in the casing in any suitable manner. In the apparatus illustrated I have shown the part 1 beaded or flanged, as at 10, for the support of the plate 9, while the plate 8 may be supported on the top edge of the part 1, the part 3 being beaded or flanged as at 12, so as to secure

ly lock the same in place. I have shown a tube 11 arranged between and connecting the two parts, it being understood that this may be secured to one or both, as desired, 5 the same serving to provide a valve stem guide as hereinafter described. However, I have found that the tube may be omitted, if preferred, as it is not strictly essential.

Between the plates I prefer to arrange a 10 sponge 14, or any equivalent porous or cellular material which may be satisfactory for the purpose. Projecting into the casing at any suitable point is a pipe or conduit 15, which in the construction shown is extended 15 through the top and provided with an off-set portion 16 adjacent the bottom, the pipe 15 in the construction shown being connected with a source of vapor supply, for example the automobile radiator, as will be 20 more fully described hereinafter. There is also provided a discharge pipe 17, preferably arranged adjacent the upper portion of the device, the same in the construction illustrated being located at the top of the 25 closure 3. A drain pipe 18, arranged near the lower portion of the device is also provided, but the escape of vapor from the device is normally prevented by a valve 19 of the desired type, or its equivalent for the 30 purpose. As shown, valve 19 is automatically operable to maintain the desired amount of fluid in the apparatus, or to prevent any excessive amount. Referring particularly to Fig. 1, the valve is mounted on 35 a valve stem 20, which carries a float 21, the valve stem projecting through and being guided by the tubular sleeve 11. If it is desired to arrange the valve so that it may be controlled from the exterior of the 40 device so as to permit draining the same, a very convenient construction is a pin or stem 22 arranged so that it projects to the exterior of the device and may be conveniently manually manipulated.

45 If desired, a baffle 23 may be arranged in the casing below the float, the same being provided with apertures therethrough. The baffle or splash plate tends to prevent the splashing of the contained liquid and accidental raising of the float when driving over rough roads where the device is applied to an automobile or other vehicle.

The apparatus shown is connected to the engine, generally at some point between the 50 carburetor and the intake ports or intake manifold. A simple and convenient construction is a gasket or tubular member 24, arranged to be secured in place by the bolts or screws 25, which may also serve to secure 55 the carburetor to the manifold. The gasket is provided with a tubular bore 26, and the pipe 17 connected thereto so as to communicate with the interior. The gasket as illustrated is provided with a removable side 60 part 27, secured in place by screws 28 or the

like so that the connection may be removed without removing all of the gasket 24. An additional port, which is shown closed with a plug 29, may be provided, if desired. If desired, a valve 30 (see Fig. 5), of suitable design may be arranged between the apparatus and the gasket. I have shown the receptacle provided with an inlet at the top which is normally closed or sealed by a cap or closure 33, the inlet affording a convenient inlet for the adding of water, or other fluid if the device is not connected to the radiator or other source of moisture. In the figures, I have shown an additional pipe 34 projecting into the casing, and this is 70 connected with the crank case of the engine, 75 as will be hereinafter described.

Referring particularly to Fig. 5, the pipe 15 is shown operatively connected with a part of the cooling system of the engine, 80 which constitutes a source of moisture supply. This pipe may be connected to the cooling system in any desired manner and at any desired or suitable point. In the arrangement illustrated, the pipe 35 is connected to the tank part 36 forming part of the radiator in many well-known constructions and to which water is admitted from the engine through the intake pipe or hose 37. Most radiators are provided with a top 85 tank or container which receives the water from the engine and distributes it to the tubes of the radiator. As illustrated, the pipe 35 projects into the tank part and, adjacent the upper end in the upper part of 90 the container, is provided with an opening or with apertures for the admission of water vapor from the radiator. Generally I prefer to place a screen or straining element 38 over the opening or apertures. The part 95 may be secured in place and sealed in any suitable manner, as for example by a nut 39 and guide 40, together with suitable gaskets (not illustrated). A valve 41 may be 100 installed, as shown, if so desired. In the figure referred to I have shown the pipe 34 communicating with the pipe 41, 42, extended to the crank case. This may be connected with the breather pipe 43, or to the crank case in any other or equivalent 105 manner. The valve 44 may also be installed, if desired.

In Fig. 5 I have shown the valve 30 provided with the valve arm 50 and connected with an operating or controlling rod 51. 110 Rod 51, where the device is installed on an automobile may extend to adjacent the driver's position.

The operation of the device may be briefly described as follows:

115 Assuming that the device is installed and connected up as shown, as the engine is operated there is a suction created in the pipe 17, thereby creating a partial vacuum in the receptacle in which normally there is a 120

- supply of water or the like. The vapor is drawn from the radiator through the pipe 15 because of this partial vacuum, and the same bubbles up through the water in the 5 apparatus and passes up through the partitions 8 and 9 through the sponge 14, or the equivalent, when such is used and is drawn into the engine, thereby improving the running thereof. The advantage of having 10 moist vapor in the ingoing charge is well known and needs no detailed description nor pointing out of advantages. The cellular body or sponge 14 has a tendency to accumulate moisture and become moist and 15 tends to maintain a uniform saturation of the vapor so that substantially the same density of vapor is always provided for and supplied to the engine. If there is no water in the receptacle to start with, it may 20 accumulate therein, but when the same reaches a predetermined level, or in case of too much water coming over the pipe 18, the flow will automatically operate the float and thus control the valve 19, permitting 25 the discharge of the excess water. This also provides that, in the case of considerable condensation in the device, the efficiency is not impaired, nor is water in an excessive amount carried into the engine. 30 In case of cold weather, or at other times, it is desired to drain the apparatus, the valve may be manually opened by means of the stem portion 22. If there are any gases or vapors in the crank case in the engine, 35 these will be drawn off through the pipes referred to and through pipe 34 into the receptacle. In this connection it will be noted that the vapors in the pipe arranged as shown will also pass or bubble up 40 through the water or fluid, and all dust or dirt removed. In other words, the same will be thoroughly cooled, washed and purified. The device in this case may be drained from time to time so that the contained 45 fluid is kept clean. While I have mentioned water, obviously any other fluid suitable may be employed or used in conjunction with the water vapor.
- The device may be readily disassembled 50 for inspection or cleaning.
- Having thus described my invention, it is obvious that various immaterial modifications may be made in the same without departing from the spirit of my invention; 55 hence I do not wish to be understood as limiting myself to the exact form, construction, arrangement and combination of parts herein shown and described, or uses mentioned.
- 60 What I claim as new and desire to secure by Letters Patent is:
1. In a device of the kind described and
- in combination, a chambered receptacle adapted to contain a quantity of liquid, and having a port adapted to communicate with the intake of an engine, absorbent means in said receptacle above the level of said liquid and below said port for diffusing any vapors passed therethrough, and a conduit 65 communicating with a source of vapor supply and opening into said receptacle, whereby said vapors will pass through said diffusing means and out through said port.
2. In a device of the kind described and in combination with the radiator crank case and intake manifold of an internal combustion engine, a chambered receptacle adapted to contain a quantity of liquid, and having a port adapted to communicate with said intake means across said receptacle between said port and above the level of said liquid for saturating and diffusing any vapors passed therethrough, a conduit 70 conducting water vapors from the radiator system of the engine into said body of water in said receptacle, and a second conduit 75 conducting hydro-carbon vapors from the crank case of the engine to said body of water in said receptacle, whereby said vapors conducted to said body of water will pass therethrough, and thence pass through said diffusing means and out through said port.
3. The method of humidifying the charge delivered to the intake of an internal combustion engine, comprising conducting water and hydro-carbon vapors from separate sources of supply, successively through a body of water and a moisture-saturated porous body, and thence into said intake.
4. In a device of the kind described and in combination, a chambered receptacle made of a pair of annular members, the end of one of said members adapted to frictionally engage within the end of the other member, means for detachably connecting said members together at said telescoping ends, inturned beads formed on each of said members intermediate the ends of the casing, apertured plates adapted to be arranged across said casing and to engage against said beads to prevent displacement of said plates, absorbent material in said casing between said apertured plates, means for introducing water vapor into the bottom of said casing whereby it may diffuse upwardly through said absorbent material, and an outlet at the upper end of said chamber and adapted to communicate with the intake manifold of an internal combustion engine.
- In testimony whereof, I have hereunto signed my name.

JOHN F. FUTCHER.
